UNITED STATES PATENT OFFICE.

ERNEST J. HUBBERT, OF BILLINGS, MONTANA.

HEAT-EXCHANGE DEVICE.

Application filed November 6, 1923. Serial No. 673,171.

To all whom it may concern:

Be it known that I, ERNEST J. HUBBERT, a citizen of the United States, residing at Billings, in the county of Yellowstone and State of Montana, have invented certain new and useful Improvements in Heat-Exchange Devices; and I do hereby declare the following to be a full, clear, and exact description of the invention, such as will 10 enable others skilled in the art to which it appertains to make and use the same.

The present invention relates to improvements in waste heat device for furnaces and the like in which the heat usually lost 15 through the stack is recovered in a large measure and applied to the preheating of the cold air.

It is a well known fact among heating engineers that only about 50% of the heat 20 generated from combustible fuel in the average appliance is absorbed and transmitted to its actual station of usefulness. This applies more particularly to domestic house heating appliances, and especially to 25 hot air furnaces.

When the coal burning furnace is converted to natural gas the average efficiency is around 60%, leaving 40% to be wasted through the chimney into the atmosphere.

The difficulty is almost entirely traceable 30 to the lack of heat absorbing surface or metal walls that will pick up the heat after combustion has taken place so these units can be carried by circulation through channels intended to convey them to the different points of utility. It is with the purpose in mind of adding additional absorbing surface and travel to the hot air furnace and arresting the waste heat by passing 35 it over sheet iron walls, and in turn passing the air circulation over these elements, which by gravitation returns them to the dome of the furnace for redistribution.

It is an object of the invention to produce 40 a device of simple construction, inexpensive to make commercially and of compact design whereby it may be coupled to the usual heating systems without requiring any alteration therein, except possibly in 45 the rearranging of piping; the device being adapted to receive the heat products passing through the smoke pipe, through which the device is included, and for causing these 50 products to give up to the cold air which is

circulated through the device a large degree of the heat which is usually dissipated.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side view of a furnace and draft and heating pipes with the invention installed in connection therewith.

Figure 2 is a top plan view, with parts broken away, of the improved device.

Figure 3 is a central vertical section taken on the line 3—3 in Figure 2.

Figure 4 is an end view of Figure 3 taken from the left as shown in Figure 2.

Figure 5 is a cross section taken on the line 5—5 in Figure 2, and

Figure 6 is a longitudinal section taken on the line 6—6 in Figure 3.

Referring more particularly to the drawings, and for the present to Figure 1, 7 designates a furnace having a number of pipes 8 for conveying the heat therefrom to the rooms of a building to be heated or to destinations of use. The furnace is further provided with a smoke pipe 9 connecting with the chimney 10 and a cold air pipe 11 is shown as connecting with the base of the furnace.

In accordance with the invention the improved device indicated at 12 is coupled in 90 the smoke pipe 9 and is actually connected with the smoke zone of the furnace by the pipe section 13. The device is further connected with the dome of the furnace by the pipe 14 having the damper 15 and with the 95 heat conveying pipes by the pipe section 16 having the damper 17. Cold air, for instance from the pipe 11, is introduced into the device by means of the pipe section 18.

As shown more particularly in Figures 2 to 6 inclusive, the improved device is comprised within the shell or casing previously referred to as 12 and being of substantially rectangular form in cross section as indicated in Figure 5, except that at the upper 105 portion the shell or casing is curved or arched to a central high point. The casing is closed by heads 19 and 20 suitably affixed therein. The head 19 is perforated to receive the pipes 13 and 14 and the pipe 14 110

connects with a tube 21 situated in the upper portion of the casing and extending substantially from one head to the opposite head, but being closed at the head 20 and 5 open axially to the pipe 14 and peripherally to the pipe section 16. The interior of the tube 21 connects by means of a number of channels 22 formed by spaced longitudinal plates 23 and 24 with a cold air space 25 at 10 the base of the casing 12 and below a perforated false bottom 26 which separates the cold air space 25 from the hot air circulating chamber 27. The false bottom 26 is provided with spaced rows of perforations 15 28 extending in a longitudinal direction and being enveloped by the base portions of the channels 22. The channels extend upwardly from the perforated false bottom 26 in substantial parallelism and the channels are 20 spaced apart, preferably a uniform distance, providing spaces therebetween for the circulation of the smoke and hot waste products from the furnace. The upper ends of the tubular channels, or rather the plates 23 25 and 24, which constitute and provide these channels, are curved mutually toward the tube 21 at their upper ends and in conformity with the arched dome like top of the casing 12, the tubular channels communicating 30 with the tube 21 and delivering the air thereto after passage through the channels. The tube 21 is thus perforated to receive the upper ends of the plates 23 and 24 but the imperforate portions of the tube 21 35 between the points of the connection prevent any access of the smoke or waste heat products from the furnace from actually getting into the tube 21. The tubular channels 22 are closed at their ends by strips 29 40 and 30, and the various parts may be welded or secured together in any desired manner. The parts are, moreover, preferably formed of sheet metal of desired thickness, but I do not wish to be restricted to this material 45 alone, as it is quite possible to make the device from other material and any other various sizes and shapes. The smoke pipe 9 connects with the head 20 by means of the cone 31 in order to condense the products 50 and direct them into the smoke pipe.

In the use of the device, the casing is coupled as shown in Figure 1, and the furnace being in operation, smoke and the other heat products will pass through the device on the 55 way to the chimney. The heat in these products is customarily wasted, but in entering the device through the pipe 13, such normally wasted heat products will pass through the spaces 27 from end to end of the casing 60 12 and will be brought into active contact with the long plates 23 and 24 which confine the narrow channels 22. The heat products will then seek exit through the cone 31 and smoke pipe 9, but they will be received

in a much cooler condition, and after they have given up a large per cent of their heat to the cold air which enters the base of the casing 12 by means of the cold air pipes 11 and 18. The cold air will ascend through the perforations 28 and the channels 22 and 70 will create a considerable draft as this cold air becomes heated in the channels and rises into the tube 21. From this tube the heated air is delivered by the pipe 14 to the furnace dome or by the pipe 16 to the heat conveying or distributing pipes directly. By adjusting the dampers 15 and 16 the heated air from the device 12 may be diverted to either destination as required. By cold air regulation with a damper, such as 32 in the 80 cold air pipe, the stack temperatures can be reduced to a minimum thus effecting a saving of practically all the available heat units. The excess waste heat products of combustion are exhausted through pipe 9 85 and into the stack or chimney.

The invention will be found particularly adapted to heating plants where natural gas is used, but no doubt it will give equally good results where coal, or other fuel is employed. 90

It is obvious that various changes and modifications may be made in the details of construction and design of the above specifically described embodiment of this invention without departing from the spirit thereof, such changes and modifications being restricted only by the scope of the following claims. 95

What is claimed is:

1. A device as described comprising a casing, heads in the ends thereof, sections of a furnace smoke pipe coupled through opposite heads, a tube at the upper portion of said casing, a perforated false bottom spaced above the true bottom of the casing and providing an air space therebetween in communication with a source of cold air supply, plates secured at opposite sides of the perforations of the false bottom and providing channels therebetween communicating with the tube, a pipe connecting with the tube and the dome of the furnace, and a second pipe connecting with said tube and directly with points of use. 100

2. A device as described comprising a casing having an arched top portion, a head secured in the casing, sections of a smoke pipe connected with opposite head, a tube in the upper portion of the casing, air channels connected at their upper ends with said tube and being curved mutually at opposite sides to conform to the arched top of the casing, an air chamber at the base of said casing in communication with the lower ends of said channels, said channels being spaced apart. 110 120 125
